UNITED STATES PATENT OFFICE.

JOHN M. CALDWELL, OF ANNISTON, ALABAMA.

DESIGN FOR A BADGE.

SPECIFICATION forming part of Design No. 22,307, dated March 28, 1893.

Application filed February 18, 1893. Serial No. 462,920. Term of patent 3½ years.

To all whom it may concern:

Be it known that I, JOHN M. CALDWELL, of Anniston, Alabama, have invented a new and useful Improvement in a Design for Badges, of 5 which the following is a specification.

My invention relates to a design for badges, and it consists essentially of a badge bearing on its face, spaces inclosed by a marginal line surmounted by the likeness of Columbus.

10 The drawing represents a view of the badge illustrating my design.

The essential characteristic of the design consists of a badge of circular form, and bearing on its face two spaces a , a' , one above the

other, each inclosed by a continuous marginal 15 line, and a likeness a^2 of Columbus the latter surmounting the upper space a as shown.

Having thus described my invention, what I claim is—

The design for a badge as described and 20 illustrated by the accompanying drawing.

In testimony whereof I hereunto set my hand, this 18th day of February, 1893, in the presence of two attesting witnesses.

JNO. M. CALDWELL.
